8941

8941

UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 14,513, dated December 25, 1883.

Application filed October 27, 1883. Term of patent 3½ years.

To all whom it may concern:

Be it known that I, MARY TURNER, of the city, county, and State of New York, have invented and produced a new and original Design for a Pattern of a Girl's Costume, (numbered 8,941;) and I do hereby declare that the engraved prints accompanying this specification convey to any one accustomed to using paper patterns a clear understanding of how to a garment made up by the pattern will appear.

The design shows a double box-plaited skirt, jacket-fronts, with a deep drooping vest that is Shirred at the neck and slightly over-

lapped at the sides by the jacket-fronts, and a half-fitted back with plaits at the lower ends of its seams. Coat-sleeves are added.

What I claim as my invention, and desire to secure by Letters Patent, is—

The design for a girl's costume, as shown in the engraved prints accompanying this specification.

MARY TURNER.

Witnesses:

MARCELLUS CARLETON SHATTUCK,
ALFRED FRANCIS.
